INVENTOR

UNITED STATES PATENT OFFICE

95,583

DESIGN FOR A SHOE

John A. Galway, New York, N. Y.

Application February 25, 1935, Serial No. 55,807

Term of patent 3½ years

To all whom it may concern:

Be it known that I, John A. Galway, a citizen of the United States of America, residing in Manhattan, county of New York, and State of New York, have invented a new, original, and ornamental Design for a Shoe, of which the following is a specification, reference being had to the accompanying drawing, forming part thereof, wherein,

I claim:

The ornamental design for a shoe, substantially as shown.

JOHN A. GALWAY.
